DOORLOCK

Hebart J. Hendrick, New Haven, Conn.

Application September 22, 1930
Serial No. 483,458

10 Claims. (Cl. 70—29)

This invention relates to door locks and has for one of its objects to produce a lock which will so secure a door that the door cannot be opened with a jimmy. To this end the latch member 5 is carried by the jamb and the mechanism engageable therewith releasable by means which also may retract the latch carried by the door.

A further object of the invention is to provide a lock which may be arranged for use with 10 either right or left hand swinging doors and with doors which swing either in or out by simple rearrangements of certain of the lock parts.

Still further objects are to provide a lock of 15 this type having a night latch arrangement by which one of the door knobs may be made operative or inoperative to release the lock, and to provide such a lock which is readily key operated.

For a more complete understanding of this 20 invention reference may be had to the accompanying drawings in which

Figure 1 is a fragmentary section through a portion of the door and the lock mechanism carried thereby, parts being broken away, the mechanism being in door-open position.

Figure 2 is a front end elevation of the same portion of the door.

Figures 3, 4 and 5 are sections on the correspondingly numbered section lines of Figure 1, 30 the cover plate being in position.

Figure 6 is a fragmentary vertical section through the door jamb and latch casing showing the latch mechanism in elevation.

Figure 7 is a horizontal section through the 35 door and jamb mechanism, line 7—7 of Figure 6 being a section line for the jamb mechanism, the door being in slightly open position.

Figure 8 is a view similar to Figure 7, but showing the door closed.

Figure 9 is a view similar to Figure 8, but 40 showing the positions of the parts when the door knob is turned to latch-releasing position preparatory to opening the door.

Figure 10 is a view similar to a portion of Figure 8 but with parts arranged for an oppositely 45 swung door.

Figure 11 is a view similar to Figure 1, but showing one of the door knobs turned to door-releasing position.

Figure 12 is a fragmentary perspective showing 50 certain of the parts in the door.

Figure 13 is a fragmentary section through a door and jamb showing a lock mechanism of a modified form in locking position.

Figure 14 is a view similar to portions of Figure 14 illustrating the action of the jamb bolt 55 on the lock keeper mechanism.

As shown on the drawings, a portion of the mechanism is contained in a lock casing 20 which is mortised flush into the edge of a door 60

in the customary manner, and a latch casing 21, which is mortised flush into the adjacent jamb. A latch or bolt 22 is provided, this bolt being located in the latch casing 21 rather than in the lock casing 20. The bolt 22 is pressed outwardly as by a suitable spring 23 so that a considerable portion of its outer end projects beyond the jamb unless the bolt is pressed inwardly, as in Figure 9. The bolt may be provided with a pair of pilot latches 24 movable inwardly by contact with the end of the door as shown in Figure 7. The outer end portion of the bolt is recessed, as shown in Figure 6, so as to form shoulders 25 adapted to be engaged by a keeper 26 located within the lock casing 20. The keeper is pivoted as at 27 on an ear 28 projecting inwardly from a side of the lock casing. A similar ear 29 is mounted on the opposite side of the casing for use if the lock is to be adapted to a door opening in the opposite direction as illustrated in Figure 10.

A suitable spring 30 is provided to press the keeper 26 into position to engage the shoulders 25 on the bolt 22 in the manner indicated in Figure 8. The keeper 26 may be made with a

comparatively narrow body portion 31 on the outer end of which is a vertically elongated head portion 32, the upper and lower edges of which engage the shoulders 25 of the bolt 22, the body 31 of the keeper entering the recess in the end

of the bolt between the shoulders 25, the keeper being preferably narrower vertically than its mating latch portion in order to permit considerable sagging of the door without causing them to fail to cooperate. The shoulders 25 also have sufficient clearance behind them to allow for swelling and shrinking of the door. When

the bolt is thus engaged by the keeper, the former is positively held against retraction into the latch casing 21 so that retraction of the bolt

by means of a jimmy is thus prevented. As long as the bolt projects across the clearance between the door and the jamb, and into the lock casing, it is impossible to open the door.

According to the invention, mechanism is provided to release the keeper from engagement with the bolt and to thrust the bolt back into the latch casing against the pressure of the spring 23 so that the door may be swung open.

To this end an actuating slide 35 may be employed, this member being illustrated in perspective in Figure 12. As therein shown, it may comprise a vertical plate 36 having a stiffening rim 37 around three sides thereof. To the fourth side is secured a facing plate 40 which fits in an opening 38 in the face 39 of the lock casing 20 which is flush with the edge of the door.

The facing plate 40 prevents entry of dust or other foreign matter into the lock casing when the door is open. The face 39 may be provided

65

115

120

with a striker portion 400 for the latch. This opening 38, as shown in Figure 2, is made in the form of a C, leaving a tongue 41 projecting from one side of the wall 39. The facing plate 40 is likewise in the shape of a C so as to fit within this opening. When the keeper is pivoted to the ear 29, as in Figure 10, the facing plates 39 and 40 are inverted as is also the latch casing 21 with its bolt.

- 10 At the end of the vertical plate 36 remote from the facing plate 40 is a neck 42 which extends rearwardly and terminates in a cross-head 43, the ends of which are guided between pairs of ribs 44 formed on or secured to the inner surfaces of the side walls of the lock casing 20. The bottom edge of the facing plate 40 in like manner slides on and is guided by a rib 45 on each side wall of the lock casing. The keeper 26 is located within the lock casing behind the tongue 41 so that when the actuating slide 35 is moved rearwardly in the lock casing, the keeper projects through the opening in the facing plate 40, as shown in Figure 8. The forward end of the keeper is thus in a position to catch the projecting end of the bolt 22.

When the door is swung shut the leading edge of the door pushes the bolt 22 into the latch casing until the lock casing and latch casing are in line. The spring 23 then acts through the bolt 22 to push the actuating slide 35 rearwardly until the keeper 26 projects through the opening in the face plate 40 and is swung over by the spring 30 to catch the end of the bolt 22.

In order to open the door it is necessary to move the actuating slide 35 forwardly. This motion causes the edge 46 of the face plate 40 to ride on the side of the keeper 26 and thus to swing the keeper on its pivot against the pressure of the spring 30. The keeper is thus swung clear of its engagement with the bolt 22 so that the bolt is thus released for motion into the latch casing 21. Continued forward motion of the actuating slide 35 pushes the bolt 22 into the latch casing against the pressure of the spring 23 until the casing plate 40 is flush with the forward end face of the lock casing. The door is now ready to be swung open.

For the actuation of the slide 35 suitable mechanism may be provided as illustrated in Figure 1. The rearward edge of the reinforcing member 37 may be engaged by an upstanding lever 50 which rocks on its foot 51, the latter being loosely held between a lug 52 and a spring 53. The lever 50 may be rocked against the lug 52 as a fulcrum by either end of an arm 54 which is fixed on a shaft 55. As indicated in Figures 4 and 5, the rocking arm 54 may be supplied in duplicate, these arms being separately mounted on short shafts 55 which are respectively connected with the door knobs 56 on opposite sides of the door. By this structure one of the rock arms 54 may be provided with locking means to prevent opening of the door by its corresponding knob, while the other rocking arm 54 is free to operate by the turning of its respective knob 56.

As is customary in door construction a night latch mechanism may be provided actuatable to prevent opening of the door by the outside door knob. To this end a pair of suitable plungers 60 and 61 are mounted so as to project through the end wall 39 of the lock casing. These plungers are pivotally connected at their inner ends with opposite ends of a rock arm 62 which may be pivoted as at 63. This rock arm carries

a lug 64 on its rearward edge which is adapted to enter a recess 65 in a boss 66 by which one of the arms 54 is mounted on its shaft 55. It is evident from inspection of Figure 1 that if the plunger 60 is pressed rearwardly, the lug 64 will be retracted from its recess, leaving both of the arms 54 free to be operated by their respective knobs 56. If the plunger 61 is pressed in, the lug 64 is moved into the recess 65 thus locking one of the arms 54 against rotation and preventing the opening of the door by one of the knobs 56, the other knob being free for operation. The rock arm 62 can be readily arranged on either side of the plungers 60 and 61 so as to co-operate with either one or the other of the arms 54. Thus the night latch can be adapted to operate with either one or the other of the knobs 56 according to which one is the outside knob of the door.

The actuating slide 35 is also adapted to be operable through the use of a door key. To this end a lock of any convenient construction may be provided, such a lock being illustrated at 70. The lock may be adapted to be screwed into place as illustrated in Figure 3, a suitable detent 71 being provided to engage the side of the lock barrel after it is in place and to hold it in place. The detent may be pressed firmly against the side of the barrel as by a screw 72, the head of which is flush with the edge of the door so that the fastening screw 72 can be turned only when the door is opened.

The lock may be provided with a projecting arm 75 adapted to be swung by operation of a key in the lock. As shown in Figure 1, this projection may extend downwardly so that when it is swung by actuation of the lock key, it engages the rearward face of the crosshead 43 and thus moves the entire actuating slide 35 forwardly a sufficient distance to push the bolt 22 home so as to permit the opening of the door. The actuating slide 35 can thus be operated by either one of the arms 54 or by the arm 75, these latter members being in turn operable, respectively, by the door knobs 56 and a key which fits the lock 70.

A modified form of the invention is illustrated in Figures 13 and 14. In this form a bolt or latch 80 is provided, pressed outwardly as by a suitable spring 23. Mortised within the door is a lock casing 20 within which is mounted mechanism for gripping the projecting end of the bolt 80 so as to hold it positively against retraction until the gripping means are released by mechanism contained in the lock casing 20. The lock casing may contain a pair of horizontal lever arms, 84, 85, one above the other, each of these arms having a tooth 86 projecting from its arm toward the other arm. Each tooth is beveled as at 87 so as to present a sloping face forwardly toward the bolt 80. The projecting end of the bolt, which may be made in two parts similar to the bolt 22, is provided with recesses 88 in its upper and lower faces to receive respectively the teeth 86.

As shown in Figure 13, the lever arms 84 and 85 may be pivotally mounted within the lock casing as at 90 and 91. A pair of springs 92, 93 are provided by which the arms are resiliently pressed toward each other. These springs tend to hold the teeth 86 within the recess 88 and thus to retain the bolt 80 against retraction as shown in Figure 13. In order to release the bolt, the levers 84 and 85 must be swung back away from each other to withdraw the teeth 86.

from the recesses 88. For this purpose the levers 84 and 85 are provided with cam portions 94 and 95 which may be engaged by the outer end of the slide 50 when it is actuated by one 5 of the knobs to release the bolt in the same manner as described with reference to the construction shown in Figures 1 to 12 inclusive.

When the door is shut the catch or bolt 80 is pressed against the teeth 86 which are thereby 10 separated sufficiently for the bolt to pass there-between, whereupon they snap into the recesses 88 and act as a keeper to prevent withdrawal of the bolt except by actuation of the slide 50, either by turning one of the door knobs or by 15 turning the key.

To reverse the lock it is necessary only to 20 reverse the face plate and to shift the night latch to engage in the other knob arm 54 to provide for right, or left, in or out swing of the door.

Certain embodiments of this invention having 25 thus been described, it should be evident to those skilled in the art that various changes and modifications might be made therein without departing from the spirit or scope of the invention 30 as defined by the appended claims.

I claim:

1. A door lock comprising a rotatable knob, a latch element for mounting in a door jamb and 35 spring means for yieldingly holding said element projected outwardly of the face of said jamb, means mounted in a door for enclosing and holding against retraction the projecting portion of said latch back of the edge of said door when said door is shut, and means carried 40 by the door and actuatable by rotation of said knob to release said holding means when the door is to be opened.

2. A door lock comprising a rotatable knob, a latch element for mounting in a door jamb and 45 spring means for yieldingly holding said element projected outwardly of the face of said jamb, means mounted in a door for enclosing and holding against retraction the projecting portion of said latch back of the edge of said door when 50 said door is shut, and means carried by the door and actuatable by rotation of said knob to release said holding means and to eject said latch from said door and into said jamb to permit the door to be opened.

5. The combination with a latch casing for mounting in a door jamb, a latch carried in said casing, and a spring for yieldingly pressing said latch to extend outwardly of said casing, of a door lock casing having an opening in its edge 55 face to receive the projecting portion of said latch when the door is closed, a keeper carried within said lock casing for interlocking engagement with said projecting latch portion a rotatable knob, and means actuatable by rotation of 60 said knob for releasing said keeper from said latch.

4. The combination with a latch casing for mounting in a door jamb, a latch carried in said casing, and a spring for yieldingly pressing said 65 latch to extend outwardly of said casing, of a door lock casing having an opening in its edge face to receive the projecting portion of said latch when the door is closed, a keeper carried within said lock casing for interlocking engagement with said projecting latch portion, and means for pushing said latch back into its casing to permit the door to be opened, said pushing means including a rotatable knob, a face plate having a portion movable inwardly from 70 a position flush with the remainder of said plate

to the interior of the lock casing, said portion substantially closing said opening when in its flush position, and means actuatable by rotation of said knob to move said plate portion outwardly to its flush position.

5. The combination with a latch casing for mounting in a door jamb, a latch carried in said casing, and a spring for yieldingly pressing said latch to extend outwardly of said casing, of a door lock casing having an opening in its edge face to receive the projecting portion of said latch when the door is closed, a keeper carried within said lock casing for engagement with said projecting latch portion, a member movable in said lock casing toward and from a position in which a face thereof is flush with said edge face and substantially fills said opening, said member being actuatable to move said keeper out of engagement with said latch and to push said latch out from said lock casing, a rotatable door knob, and connections from said knob for actuating said member.

6. The combination with a latch casing for mounting in a door jamb, a latch carried in said casing, and a spring for yieldingly pressing 100 said latch to extend outwardly of said casing, of a door lock casing having an opening in its edge face to receive the projecting portion of said latch when the door is closed, said lock casing having a lug on each side wall, a latch 105 keeper selectively pivoted to either of said lugs to swing into or out of engagement with said latch, a spring pressing said keeper into latch-retaining position, a face plate for said lock casing having an opening to receive said latch and 110 a portion extending forwardly of said keeper, said face plate being reversible in accordance with the position of said keeper, a slide in said lock casing movable to retract said keeper and then to press said latch into its casing, said 115 slide having a reversible face plate mating the opening in said casing face plate and engageable with said latch, and means for actuating said slide.

7. The combination with a latch casing for 120 mounting in a door jamb, a latch carried in said casing recessed to form a pair of spaced aligned shoulders, of a door lock casing having an opening in its edge face to receive said latch, a keeper in said casing having a body portion movable 125 between said latch shoulders and an elongated edge portion for engagement with the inner faces of said shoulders to prevent retraction of said latch into its casing, and means actuatable to withdraw said keeper to permit retraction of 130 said latch.

8. The combination with a latch casing for mounting in a door jamb, a latch carried in said casing, and a spring for yieldingly pressing said latch to extend outwardly of said casing, of a 135 door lock casing having an opening in its edge face to receive the projecting portion of said latch when the door is closed, a pair of spaced hook elements in said casing movable to engage in opposed openings in said latch to hold said 140 latch against retraction into its casing, spring means for holding said hooks in latch-retaining position, said latch and hooks having cooperating portions causing said hooks to separate by pressure of said latch thereon as projected by 145 its spring, and means actuatable to retract said hooks to release said latch.

9. The combination with a latch casing for mounting in a door jamb, a latch carried in said casing, and a spring for yieldingly pressing said 150

latch to extend outwardly of said casing, of a door lock casing having an opening in its edge face to receive the projecting portion of said latch when the door is closed, a pair of spaced hook elements in said casing movable to engage in opposed openings in said latch to hold said latch against retraction into its casing, spring means for holding said hooks in latch-retaining position, said latch and hooks having cooperating portions causing said hooks to separate by pressure of said latch thereon as projected by its spring, and means actuatable to retract said hooks to release said latch, and to thereafter press said latch into its casing to permit the door to be opened.

10 10. The combination with a latch casing for mounting in a door jamb, a latch carried in said casing, and a spring for yieldingly pressing said

latch to extend outwardly of said casing, of a door lock casing having an opening in its edge face to receive the projecting portion of said latch when the door is closed to prevent opening of the door, an element movable within said door lock casing to contact with the end of said latch to retract the same and permit the door to be opened, a footed lever engageable with said element for actuating said element, a spring engaging the foot of said lever for holding said lever retracted, a door knob spindle in said lock casing, and an arm carried by said spindle rockable against said lever for moving said lever against the action of said last mentioned spring to actuate said element on turning of said spindle.
